UNITED STATES PATENT OFFICE.

ULYSSE N. TREMBLEY, OF SOUTH LAWRENCE, MASSACHUSETTS, ASSIGNOR TO DRAPER CORPORATION, OF HOPEDALE, MASSACHUSETTS, A CORPORATION OF MAINE.

TEMPLE-THREAD PARTER FOR LOOMS.

1,394,652.

Specification of Letters Patent. Patented Oct. 25, 1921.

Application filed February 14, 1921. Serial No. 444,675.

To all whom it may concern:

Be it known that I, ULYSSE N. TREMBLEY, a subject of the King of Great Britain, and resident of South Lawrence, county of Essex, State of Massachusetts, have invented an Improvement in Temple-Thread Parters for Looms, of which the following description, in connection with the accompanying drawing, is a specification, like characters on the drawing representing like parts.

This invention relates to improvements in loom temples which are provided with thread parters and the object thereof is to provide novel means for rendering the thread parting mechanism inoperative during such portion of the time of the operation of the loom as the function of the thread parter is unnecessary.

In automatic filling replenishing looms a temple is employed which is provided with a thread parter for cutting off, adjacent the selvage of the cloth, the loose ends which are present after transfer of the bobbin or cop takes place. In the majority of such looms the thread parter works continuously and is thus subject to wear tending to render it dull and inefficient. The present invention is designed to provide a novel means for preventing the operation of the thread parter except for a predetermined number of actuations immediately after transfer takes place so that the life and efficient operation of the thread parter will be maintained for a long period.

I am aware that heretofore certain mechanisms have been devised for accomplishing this purpose, such as those disclosed in Patents No. 630,236 Joy August 1, 1899, and Stimpson No. 704,715 July 15, 1902.

The object of the present invention is to provide a novel means which will more effectively lock the thread parter in inoperative position than those heretofore devised.

A further object of the invention is to provide a thread parter for loom temples in which the usual spring for moving the thread cutting blade to open position will be eliminated thereby preventing the temple thread parter from becoming inoperative by reason of spring breakage.

A further object of the invention is to provide a temple thread parter with a detent which is provided with means tending normally to withhold it from locking relation to the thread parter, and with means

operated by successive movements of said thread parter for moving said detent into locking position.

Other objects and features of the invention will more fully appear from the following description and the annexed drawings and will be pointed out in the accompanying claims.

A preferred embodiment of my invention is illustrated in the annexed drawings in which,

Figure 1 is a side elevation of a loom temple and thread parter illustrating the preferred form of my invention;

Fig. 2 is a plan view of the same; 70

Fig. 3 is a rear elevation; and,

Fig. 4 is a detail vertical sectional view through a portion of the head showing the assembled relations of the thread parter and locking mechanism therefor. 75

The loom temple which is illustrated in the accompanying drawings may be and is of the usual type comprising a pod 1 provided with a shank 2 which is slidably mounted in a stand 3 adapted to be secured to the breast beam of the loom, the usual spring (not shown) being provided for holding the temple and thread parter in rearward position. The usual heel 4 is secured to or formed integral with the pod 80 and is adapted to be engaged by the lay upon each beat-up.

A temple roll or rolls 5 are mounted within the pod in the customary manner. The temple is provided with a cap 6 which is secured to the pod by a bolt 7. In the preferred construction illustrated the cap is provided with a slot 8 in which the stationary cutting blade of the thread parter is secured by a screw 9 or other suitable fastening. 90

The thread parter comprises a cutting blade 10 which is pivotally mounted upon a stud 11 and is provided with a forwardly extending arm or actuator 12 which desirably is rearwardly curved and is provided at its end with lateral extensions and enlargements 13 forming a counterweight which normally tend to hold the cutting blade in open position, and which lie in 105 advance of the heel 4 so that the counterweighted end 13 of the actuator is adapted to be engaged by the lay upon its beat-up in advance of the engagement of the lay with the heel 4 of the temple. 110

The counterweight desirably may be substantially cylindrical in form so that it will present a relatively broad face for engagement with the lay. By reason of this construction the usual springs which hold the thread parter in open position are eliminated and a construction provided which will not be subject to material wear or likelihood of breakage during the operation of the loom.

One of the principal features of the invention is to provide means for locking the thread parter in inoperative position during such portion of the operation of the loom as the function of the thread parter is not required. In the preferred construction illustrated herein a bracket 14 is secured to the head or cap 6 by a screw 15 and is desirably provided with a boss 16 underlying and engaging an extension 17 of said cap or head. The bracket 14 desirably also is provided with a laterally extending boss 18 in which a detent 19 is slidably mounted. The upper face of the detent 19 is provided with a series of teeth 20 which are adapted to be engaged by a pawl and dog which will hereinafter be described.

A lug 21, projecting downwardly from the detent 19 through a slot 22 in the boss 18, is engaged by a spring 23 which is coiled about a stud 24 projecting outwardly from the bracket 14.

The detent 19 is so positioned that when it is forced inwardly its end will lie in the path of the actuator 12 and will retain it in inoperative position illustrated in dotted lines in Fig. 1 and prevent the same from oscillation. The spring 23, however, normally tends to force the detent 19 out of locking relation to the actuator 12 into the position illustrated in Figs. 1, 2 and 3.

Any suitable mechanism may be employed for forcing the detent into locking position upon a predetermined number of movements of the actuator. In the preferred construction illustrated herein a plunger 25 is reciprocably mounted in a suitable way in the temple head. The way may conveniently be formed by grooving the under-face of the extension 17 of the head adjacent the portion which engages the shank 2.

The plunger 25 rests at its lower end upon the actuator and at its upper end engages one arm 26 of a lever which is pivotally mounted upon a stud 27 mounted in the bifurcated upper end 28 of the bracket 14. The other arm 29 of said lever is bifurcated at its end and connected by a stud 30 to one end of a link 31, the other end of which is pivotally connected to a stud 32 in one arm of a bell crank lever 33 which is fulcrumed upon a stud 34 carried by a bifurcated lug 35 extending laterally from the bracket 14. The other arm of the bell crank lever 33 is pivotally connected by a stud 36 to a pawl 37

having a tooth 38 engaging the teeth 20 of the rack 19. The pawl 37 desirably is provided with an upwardly extending web 39 having at its upper end laterally extending flanges 40 which overlie a locking pawl for the rack for a purpose hereinafter to be described.

The bell crank lever 33 desirably is provided near its fulcrum 34 with an extension 41 which is engaged by one end of a spring 42, the other end of which abuts against the bracket 14 and tends to force the pawl 37 outwardly. It is obvious, therefore, that the vertical swinging movement of the actuator will act through the plunger 25 to oscillate the lever arm 26 thereby causing the opposite arm of the lever, acting through the link 31, to oscillate the bell crank lever 33 thereby forcing the pawl 37, which engages the teeth 20 of the rack 19, forward and advancing the rack step by step.

In order to lock the rack against reverse movement a dog 43 is provided having a toothed end which engages the rack. The dog 43 is provided with arms 44 which are pivotally mounted upon studs 45 in ears 46 which extend upwardly from the boss 18, the pawl 37 reciprocating between said arms 44. The flanges 40 upon the pawl 37 overlie the arms 44 so that when the dog 43 is raised, the arms 44 will engage said flanges and raise the pawl 37 out of engagement with the teeth 20 of the rack 19. By thus disengaging the dog 43 and the tooth 38 of the pawl 37 from the rack 20, the detent may be quickly released under the pressure of the spring 23 so that it will be at once withdrawn from locking engagement. Such release desirably is accomplished at the time transfer takes place and means are, therefore, provided for releasing the dog and pawl from some movable part of the loom which operates in conjunction with the transferring mechanism.

As illustrated herein the dog 43 is provided with a laterally extending rod or stem 47 which lies in the path of a bar 48 which is connected to and operated by the controller of the loom. The mechanism is so arranged that when transfer is called for, and the controller rod actuated to position the transferring mechanism, the bar 48 will be forced upwardly against the rod or stem 47 raising it sufficiently first to disengage the dog 43 and upon further movement to cause the arms 44 of the dog to engage the flanges 40 upon the pawl 37. Further upward movement of the dog will, therefore, cause the pawl to be released from its engagement with the rack 20 so that the spring 23 may force the detent from locking position thereby freeing the actuator and permitting the counterweighted end of the same to drop into a position in which it will be engaged by the lay upon beat-up.

As this action occurs just before transfer

is effected the thread parter will begin its cutting movements at or before the transfer of the new bobbin of the shuttle is effected and will continue such cutting movements 5 for a predetermined number of beat-ups of the lay corresponding to the number of teeth in the rack of the detent. During the successive beat-ups the rack bar will, of course, be forced forward by the pawl 37 and will 10 be retained at each step of advancement by the dog 43. When the detent 19 shall have advanced so that its end projects in the path of the actuator it will engage and hold the actuator out of operative position relatively 15 to the lay until transfer is again called for. Thus the thread parter will be inoperative during a greater part of the operation of the loom and its wear will be correspondingly decreased.

20 It will be understood that the embodiment of the invention disclosed herein is illustrative in character and is not restrictive and that various modifications in form, construction and arrangement of parts may be made 25 within the spirit and scope of the following claims.

Having thus described my invention, what I claim as new, and desire to secure by Letters Patent, is:

30 1. A loom temple provided with a thread parter, a detent operable to lock said thread parter in inoperative position, means tending normally to withhold said detent from locking position, means operable upon a predetermined number of movements of said thread parter to force and to hold said detent in locking position and means for releasing said detent.

40 2. A loom temple provided with a thread parter, a slidably mounted detent operable to lock said thread parter in inoperative position, a spring tending normally to withhold said detent from locking position, means operable upon a predetermined number 45 of movements of said thread parter to force said detent into and to hold the same in locking position and means for releasing said detent.

50 3. A loom temple provided with a thread parter, a detent movable into the path of said thread parter, resilient means tending normally to withdraw said detent from the path of said thread parter, means operable

by a predetermined number of movements of said thread parter to advance said detent 55 into the path of said thread parter, means for retaining said detent in locking position and means for releasing said detent.

4. A loom temple provided with a thread parter, a slidably mounted detent operable to lock said thread parter in inoperative position, means tending normally to withhold said detent from locking position, pawl and ratchet mechanism operable by successive movements of said thread parter 60 to advance said detent to locking position and means for releasing said detent.

5. A loom temple provided with a pivotally mounted thread parter having a cutting blade and an actuating arm, a detent 70 movable into the path of said actuating arm, a plunger engaging said thread parter, pawl and ratchet mechanism operable by the movements of said plunger to position and hold said detent in the path of said actuating arm and means for withdrawing said detent from locking position.

6. A loom temple provided with a pivotally mounted thread parter having a cutting blade and an actuating arm, a detent 80 movable into locking relation to said actuating arm, means acting normally to withhold said detent from locking position, a rack on said detent, a pawl engaging said rack, means operable by successive swinging movements of said thread parter to actuate said pawl, a dog engaging said rack and means for releasing said dog and pawl.

7. A loom temple provided with a pivotally mounted thread parter having a cutting blade and an actuating arm, a detent 90 movable into locking relation to said actuating arm, means acting normally to withhold said detent from locking position, a rack on said detent, a pawl engaging said rack, means operable by successive swinging movements 95 of said thread parter to actuate said pawl, a dog engaging said rack, means on said pawl overlying said dog and means carried by said dog adapted to be engaged by a movable part of the loom mechanism to release said dog and pawl.

In testimony whereof, I have signed my name to this specification.

ULYSSE N. TREMBLEY.
